United States Patent Office.

C. H. KNOX, OF MOUNT PLEASANT, IOWA.

Letters Patent No. 92,459, dated July 13, 1869.

IMPROVED WASHING-MACHINE.

The Schedule referred to in these Letters Patent and making part of the same.

To all whom it may concern:

Be it known that I, C. H. KNOX, of Mount Pleasant, in the county of Henry, and State of Iowa, have invented an Improvement in Washing-Machines; and I do hereby declare that the following is a full, clear, and exact description of the construction and operation of the same, reference being had to the accompanying drawings, and letters marked thereon, in which—

Figure 1 is a sectional elevation of my invention.

Figure 2, a broken elevation of the central journal, showing the right and left-hand screw-threads.

Figure 3, a perspective view of the washer and its attachment, detached from the other parts of the machine.

The object of the present invention is more especially to improve the washing-machine patented by me, on the 22d January, 1867; and

Its nature consists in the novel means employed to secure the washer to the centre journal, whereby the machine can be put together with much less difficulty, and the washer held firmly in place, and so as to be removed when required.

To enable others to fully comprehend the construction and operation of my invention, I have marked corresponding parts of the same with similar letters, and will now give a detailed description.

A represents a common washing-box, which is made of wood, and similarly to the box used in the patent above referred to; and

B B show the two-part lid, to which the gearing D C and metal frame K are attached, said gearing being the same as shown in said patent.

The pinion D, however, in the present invention, is rigidly attached to the journal E, whereas in my previous patent it was removable, in order that the washer H might be detached from the gearing, above the lid B B.

Much difficulty, however, is experienced in securing the pinion D firmly enough to drive the journal E,

and at the same time permit the latter to be readily removed when it becomes necessary to lift the washer H out of the box A, which operation is frequently required.

The journal E, as now arranged, can only be removed from the top of the box, and by being drawn through its bearing F; and to provide for securing and removing the washer H, a left-hand screw, m, is cut on the journal, as shown at fig. 2, and a metal clamp, O, having a corresponding screw-thread, is turned thereon; said clamp having lugs, J J, projecting downward, and into depressions made in the top of the washer.

A right-hand-screw-thread is cut on the lower end of the journal, and a nut, K, with a corresponding screw-thread, turned thereon, thus holding said washer firmly between the clamp and nut.

This arrangement is very simple, yet important, for the reason that hot water is generally used in this kind of a machine, and if some permanent means are not employed, the washer will become loosened or detached, as there is a great strain on the pins I when giving the clothes in the box A reciprocating rotary motion.

The operation of the machine is simple, and generally well understood, requiring only that the lever R should be grasped with the hand and moved back and forth, so as to give the pinion D a suitable motion.

Having thus described my invention,

What I claim, and desire to secure by Letters Patent, is—

The combination of the washer H with the clamp G, journal E, nut K, and pinion D, said clamp and nut being arranged to turn on right and left-hand screws, and clamp the washer between them, as specified and shown.

C. H. KNOX.
